UNITED STATES PATENT OFFICE

2,543,157

BASKET

Ann Ellis, Victoria, Hong Kong

Application May 4, 1949, Serial No. 91,255

3 Claims. (Cl. 217—122)

1

This invention relates to a new and improved type of basket, comprising longitudinally disposed strips of flexible material used as ribs to form the sides, top and bottom of the basket. By being bent inwardly where the ends of the basket are to be, these ribs form also the ends of the basket. The inwardly bent portions of the ribs are secured to each other pivotally at each end of the basket by a shaft that is arranged substantially axially with respect to the basket. The ribs are spaced apart laterally by cords that extend around the basket laterally and are fastened to the ribs.

Arrangement for opening and closing the basket is provided by leaving two adjoining ribs unconnected by the cords. Centrally attached to the rib on each side of the opening so arranged is a latching member. These latching members cooperate to secure the basket closed when so manipulated. Also attached to the rib on each side of the opening is a carrying loop.

The basket comprising this invention is characterized by light weight combined with strength and large carrying capacity with security against having parcels fall out as from an open basket, by maximum ease of filling and emptying, by minimum space occupied when emptied and ready for packing, and by economy in shipping and merchandising because of its light weight and the small space into which it may be packed.

The invention will be disclosed more in detail in the following specification, reference being had therein to the accompanying drawings, in which

Figure 1 is a top elevation and shows the details of the catch;

Figure 2 is a collapsed side view;

Figure 3 is a collapsed end view;

Figure 4 is a side elevation; and

Figure 5 is a three-quarter perspective view.

Similar numerals refer to similar parts throughout the several views.

The ribs 1 and 2 (Figure 1) are shown in substantially the positions they occupy when the basket is closed. Ribs 3, 5, etc., are spaced apart from rib 1, and ribs 4, 6, etc., are spaced apart from rib 2 by cords 7 and 8. Ribs 1 and 2 are unconnected to each other by the cords 7 and 8 and form the sides of the basket opening. The latch members 9 and 10, which are fastened to the ribs 1 and 2, respectively, are shown in position to be interlocked with each other by longitudinal movement toward positions opposite each other laterally. The handle loops 11 and 12, which may be made of the same material as the

2

ribs, may be secured pivotally to the outer ends of latch members 9 and 10. The shafts 13 and 14 extend through holes drilled in ribs 1, 2, 3, 4, etc., near their respective termini, said holes being substantially in axial alignment with respect to the basket, as shown in the drawings. Said shafts may be secured against sliding out of position by any convenient means, such as by internally threaded beads 15 and 16 screwed on external threads formed on said shafts.

The basket being closed and latched by meshing of latch members 9 and 10, to open the basket members 9 and 10 are unmeshed by longitudinal movement, to the position shown in Figure 1. Handle loops 11 and 12 then are pulled apart from each other in opposite lateral directions. One advantage of the present invention is ease of opening the basket, and the large size of the opening afforded, which is as long as the basket, and may be made as wide as the basket, or any lesser width, as desired, according to how far apart the handle loops 11 and 12 are spread.

Another great advantage of the invention is that when not in use for carrying parcels, or when being shipped or stored, etc., it may be folded so as to occupy a very small space, in the following simple manner: First the handle loops 11 and 12 are pulled apart until the inwardly bent portions of ribs 1 and 2 are substantially horizontal. Then the basket is turned over, slight downward pressure exerted on its center while said handle loops are moved upward and together until the position of the described parts as shown in Figure 3 is reached.

In this condition the basket not only occupies small space, but is comparatively strongly resistant to crushing, an important item in shipping and storing in large numbers.

It will be found advantageous to make the ribs of light, strong and resilient material, such, for example, as plastic, splints of bamboo or other similarly strong wood, such as hickory or oak, strips of light metal such as Duralumin or stainless steel. Added rigidity to the top ribs is afforded by the latch members 9 and 10 secured to them. The latch members thus reinforce the top strips 1 and 2 at the points where the cords 7 and 8 are attached to said ribs and transmit added load to them.

As will be seen from the accompanying figures, the ribs, both as to their longitudinal portions and as to the inwardly bent portions thereof, are graduated in length. In the event that maximum length at the bottom of the basket is desired, the top and bottom of the basket as illus-

trated in the accompanying figures may be reversed, so that the top opening will be between two ribs here shown at the bottom, which are relatively short, and the relatively long ribs shown here at the top will be at the bottom to give maximum length there.

The cords 7 and 8 may be fastened to the ribs in several ways, such as, for example, by being tied, taped or cemented thereto, or interlaced therewith, or any other convenient manner to secure them firmly to the ribs and at such lengths as will give the desired spacing therebetween. A ready means of beautifying the basket is by twining ribbons about the cords.

What I claim and desire to secure by Letters Patent is:

1. A collapsible basket comprising a continuous, transverse peripheral series of flat strips of flexible material extending longitudinally of the basket and disposed side by side to form the bottom, sides and top of the basket, said strips being U-shaped with end portions disposed at approximately right angles to the central portion to form the ends of the basket, the ends of the strips being apertured, a pivot shaft extending through the apertures at the opposite end of all of the strips to connect said latter ends pivotally together, said U-shaped strips being of graduated length and proportionally graduated depth, with the shorter strips forming the bottom of the basket and increasingly longer strips forming the sides, and with the two longest strips at the middle of the top, handles secured to said longest strips, catch means for securing said longest strips together and a plurality of spaced cords extending around the basket from one of said longest strips to the other and secured to each of the strips to connect the strips together with the space between successive strips not greater than approximately the width of the strips, said cords constituting load-carrying means for transmitting the load carried in the basket to said handles.

2. A collapsible basket comprising a continuous transverse peripheral series of flat strips of

flexible material extending longitudinally of the basket and disposed side by side to form the bottom, sides and top of the basket, said strips being U-shaped with end portions disposed at approximately right angles to the central portion to form the ends of the basket, the ends of the strips being apertured, a pivot shaft extending through the apertures at one end of all of the strips to connect said U-shaped ends pivotally together, a second pivot shaft extending through the apertures at the opposite end of the strips to connect said latter ends pivotally together, said strips being of graduated length and proportionally graduated depth, with the shorter strips forming the bottom of the basket and increasingly longer strips forming the sides, and with the two longest strips at the middle of the top, at least the central portions of said longest strips being reinforced, carrying handles secured to said reinforced portions, catch means for securing the reinforced portions of said longest strips together, a plurality of spaced cords extending around the basket from one of said longest strips to the other and secured at spaced points to successive strips to connect the strips together, said cords being attached to the reinforced portions of said longest strips and constituting load-carrying means for transmitting the load carried in the basket to the reinforced portions of said longest strips and to said handles.

ANN ELLIS.
